Prior Art Drawing.

Primary Examiner — Mimosa De(74) *Attorney, Agent, or Firm* — Karish & Bjorgum, PC(57) **CLAIM**

The ornamental design for a stool, as shown and described.

DESCRIPTION

U.S. Design patent application Ser. No. 29/558,185, filed Mar. 15, 2016, and U.S. Design patent application Ser. No. 29/577,675, filed Sep. 14, 2016, disclose chair designs including the seats of this stool design, the disclosures of which are incorporated herein by reference.

FIG. 1 is an isometric view of the stool.

FIG. 2 is a front view of the stool.

FIG. 3 is a back view of the stool.

FIG. 4 is a left side view of the stool, the right side view being a mirror image of the left side view; and,

FIG. 5 is a top view of the stool.

The bottom view is not part of the design. The legs of the stool have an organic wood grain appearance.

1 Claim, 5 Drawing Sheets(56)
